UNITED STATES PATENT OFFICE.

ADINA SMALL, OF NEW YORK, N. Y.

WASHBOILER.

Application filed April 14, 1921. Serial No. 461,448.

To all whom it may concern:

Be it known that I, ADINA SMALL, a subject of the King of England, and resident of borough of Manhattan, county of New York, State of New York, have invented certain new and useful Improvements in Washboilers, of which the following is a specification.

The principal objects of this invention are to provide a device wherein colored and white clothes may be boiled simultaneously and yet out of contact with each other.

Another object is to provide a means for placing the clothes in the boiler without fear of scalding or burning the operator and removing them with equal facility.

Another object of the invention is to provide means for removing the water from the boiler without removing the boiler from the stove, and

Another principal object is to provide means to prevent boiling over during the time when the cover is in place.

With these and other objects in view the device described is what I consider a good means of carrying out my invention and the accompanying drawings should be referred to for a complete understanding of the specification which follows.

Fig. 1 is a perspective view of my boiler with the cover removed.

Fig. 2 is a perspective view of a part.

Fig. 3 is a perspective view of the covers.

Fig. 4, a sectional view of a relief valve.

Fig. 5 a plan view of a valve disc.

Similar reference numerals indicate like parts in all the figures where they appear.

The boiler 6 may be of ordinary shape and size and is provided with handles 7; my boiler is also provided with a plurality of slots 8, 9, 10, 11, 12, 13, 14 and 15 at the upper or open edge thereof for a purpose that shall appear later and entering in the boiler and quite close to the bottom thereof are cocks 16 and 17 by means of which water may be drawn off.

At about mid-length of the boiler I arrange a vertical partition 18 the upper edge of which is rolled to produce one portion of a hinge, and the other portions of this hinge are formed integral with cover members 19 and 20 one of which is arranged to cover each part of the boiler at the sides of the partition 18. The cover may be provided with downwardly extending flanges

19' and 20' for completely closing the boiler and knobs 21 and 22 secured to the cover members may be employed to raise the cover members.

Arranged in each cover member or section is a valve and I perforate the cover sections as indicated at 23 in Fig. 4 placing the valve members over these perforations. In producing these perforations I sever and push outward or upward and then inward at right angles certain portions of the material of the cover to form guides and stops indicated as individual members by the reference characters 24, 25, 26, 27, and 28, 29, 30, and 31, and when the pressure within the boiler is increased by the water therein boiling to produce steam, the valve discs 32 and 33 or either of them will be raised to let the steam pass out under the discs, thus preventing the lifting of the cover and the ordinary action of boiling over.

I may provide two basket members 34 as shown in Fig. 2 and each of these basket members should be provided with handles 35 and 36 having projections as indicated at 37, 38, 39 and 40 adapted to engage in the slots 12, 13, 14, 15 or 8, 9, 10 and 11 as the case may be to support the basket member above the bottom of the boiler.

With this construction the boiler may be made of any suitable material but the basket should be formed of copper or other material that will not stain the clothing.

The baskets may be of any size and other modifications may be made within the scope of the appended claim without departing from the principal or sacrificing the advantages of the invention.

Having carefully and fully described my invention what I claim and desire to secure by Letters Patent is:

The combination of a wash-boiler having a plurality of notches in two sub-divided groups in the upper edge of the boiler, of clothes receiving members having rods projecting beyond the outline thereof and serving as handles for said clothes receiving means, the projections of said rods engaging in said notches to support said clothes receiving means in the boiler.

Signed at New York, city, county and State of New York, this 30th day of March 1921.

ADINA SMALL.
